UNITED STATES PATENT OFFICE

2,683,462

QUICK-ACTING VALVE MECHANISM FOR
FLUSH TANKS

Robert G. Mutti, Logansport, Ind.

Application December 30, 1952, Serial No. 328,772

7 Claims. (Cl. 137—118)

1

This invention relates to quick acting valve mechanism for flush tanks.

While various forms of valve means have heretofore been used or proposed for controlling the discharge of water into a toilet tank as well as the associated bowl, from a water inlet pipe, the valve equipped tanks now in general use in homes are essentially of the same construction.

Such tanks now in use are provided with a water supply pipe which extends through the bottom of the tank to a substantial distance thereabove. The water supply pipe is provided with a water discharge pipe and a bowl refill tube both of which communicate with a valve controlled chamber adjacent the upper end of the water supply pipe and the valve is operated by a float.

The tank is in most instances further provided with an overflow pipe and a ball controlled opening leading to the bowl, and which ball is operative by a hand lever accessible externally of the bowl.

In the operation of such usual forms of tanks, the lever is tripped thereby raising the ball with a resulting discharge of the volume of water in the tank into the bowl for flushing same. The float descends with the lowering level of the water in the tank during such discharge of the water into the bowl, as does the ball to close the discharge opening.

The float in its descent opens the valve controlling the chamber with which the discharge pipe and bowl refill tube communicate, thereby admitting water into the tank for a succeeding flushing operation while the refill tube discharges a relatively small volume of water into the bowl. As the tank fills, the float rises and gradually closes the valve controlling said chamber, the float rising slower as it approaches its valve closed position for the reason that the volume of water being admitted through the valve is successively reduced as the valve approaches its closed position.

While this form of flush tank has met with substantial satisfaction from the standpoint of proper flushing of the bowl, objection has nevertheless been voiced to the noise resulting from the relatively long period required for complete closing of the valve, particularly due to the relatively small amount of water passing through the valve as it approaches its closed position and which produces a hissing noise.

The above noted gradual cut-off of the water supply valve with the resulting noise occasioned thereby has resulted in efforts to provide a quick

2

acting valve between the water supply pipe and the water discharge pipe and one of which efforts has resulted into a Patent No. 1,694,072, December 4, 1928.

5 While the construction disclosed in this patent provides for rapid cut-off of the water supply by means of a water pressure floating valve in addition to a float controlled valve, the objection to noise due to the gradual cut-off of 10 the discharge of water into the tank may have been substantially reduced but no provision has been made to reduce the time required for filling the tank and in which operation, some noise necessarily prevails.

15 It is accordingly a primary object of this invention to provide for filling a flush tank with water in the absence of hissing noise accompanying gradual closure of a discharge valve as well as to substantially reduce the period of time required for the tank filling operation.

A further object of the invention is to provide 20 valve mechanism for a flush tank having a water supply pipe, which includes a float controlled valve for a water discharge pipe communicating 25 with the supply pipe, and a water pressure operable valve in the supply pipe above said discharge pipe controlling the discharge of water through a second discharge pipe communicating with the supply pipe as well as a bowl refill 30 tube communicating with the supply pipe.

Other objects and advantages of the invention will become apparent in the course of the following detailed description, taken in connection with the accompanying drawings wherein:

35 Fig. 1 is a vertical sectional view as observed substantially on the plane of line 1—1 on Fig. 2; and

Fig. 2 is an elevational view as observed from the left of Fig. 1.

40 Referring now in detail to the drawings 10 designates a water supply pipe and which for reasons later to appear, is preferably formed of two axially aligned sections 11 and 12 whose adjacent ends are detachably connected as by 45 means of a swivel nut 13.

The lower end of pipe section 11 is threaded at 14 for extension through the base of a flush tank T and connections are made as is usual from the water supply with said threaded end 14.

50 Furthermore, the section 11 is provided with a flange 15 between which and the base of tank T is disposed a washer 16 as in common practice.

The water supply pipe section 11 is provided with a water discharge pipe 17 extending from 55 adjacent the upper end thereof and which may

as shown be integral with section 11 or detachably connected thereto. The discharge pipe 17 is preferably of arcuate form except adjacent its free lower end where it includes a relatively short vertical portion 17' whose free end is flared radially outwardly to provide a ball valve seat 18.

A second ball valve seat 19 is removably disposed within a countersink 20 in the upper end of pipe section 11 and is removably retained in position by means of the lower end of pipe section 12 and the nut 13.

The upper end of pipe section 12 is provided with a cap nut 21 having an aperture 22 in its top axially of the pipe sections 11 and 12.

A relatively long valve stem 23 extends through the aperture 22 and also through an axially aligned aperture 24 in the valve seat 19. The stem 23 is provided with a ball valve 25 which normally engages the seat 19 and the upper end portion of stem 23 is threaded for a substantial distance as indicated at 26 and on which is a valve adjusting nut 27.

The pipe section 12 is also provided with a water outlet pipe 28 which opens into section 12 adjacent its upper end and between the valve seat 19 and the cap nut 21 and the pipe section 12 is provided with a bowl refill tube 29 which opens into pipe section 12 in substantially horizontal alignment with the base end of water outlet pipe 28. The refill tube extends into an overflow pipe O. A float supporting lever arm 30 has its base end suitably pivotally connected to pipe section 12 and which is preferably effected by means of a band 31 extending partially around pipe section 12 and suitably secured thereto. The free ends of the band provide ears 32 between which lateral extension of lever arm 30 are pivoted as at 33.

The free end of lever arm 30 is threaded as at 34 for removable connection therewith of a float F.

The valve seat 18 on the free end of the water discharge pipe 17 is engageable by a ball valve 35 which is controlled by the float F substantially in the following manner. The ball valve 35 is freely supported on a conforming seat 36 in a plate 37.

A yoke 38 extends transversely of the lever arm 30 and is preferably provided with an aperture 39 through which the arm extends with sufficient play for the angularity of the arm in flushed position with respect to the yoke. A pair of laterally spaced rods 40 have their lower ends suitably rigidly secured to plate 37 at opposite points thereon. The rods extend vertically through lower guide eyes 41 suitably supported by opposite sides of the water discharge pipe 17 and upper guide eyes 42 supported by a band 43 encircling pipe section 11 and suitably secured thereto. The rods 40 thence extend through apertures 44 adjacent opposite ends of yoke 38.

The upper end portions of rods 40 are threaded as at 45 and nuts 46 and 47 on said threaded end portions frictionally engage the upper and lower faces of yoke 38 for a purpose later to appear.

Referring now more particularly to Fig. 1, the operation of the improved structure is as follows—

When the tank T is filled with water to a predetermined level the float supporting lever arm 30 will be in the position shown in solid lines and the valves 25, 35 will be closed as indicated in solid lines.

Upon a flushing operation of the tank by the well known means (not shown) the float F will descend with the descending level of water in

the tank with a corresponding downward movement of lever arm 30 to a position substantially as indicated in dotted lines. This downward movement of the lever arm 30 will move plate 37 downwardly to the dotted line position thereby freeing the valve 35 whereupon the water in supply pipe 10 moving in the direction of arrow a will also travel through discharge pipe 17 in the direction of arrow b and into the tank T.

The free flow of water through the discharge pipe 17 will result in a reduced pressure in pipe 18 with the result that valve 25 together with its stem 23 will fall by gravity to a position substantially as indicated by dotted lines.

Water will accordingly freely flow through both discharge pipes 17 and 28 as indicated by arrows b and c during the rise of the float F and which will be substantially rapid due to the combined cross sectional areas of both discharge pipes, and since the flow equals the square root of the pressure multiplied by the area the tank will fill in substantially less time than is required by structures now in use or as proposed in the patent referred to.

It is to be further noted that the refill tube 29 is also controlled by valve 25 and water flows through same into the bowl as long as water is being discharged into the tank from the pipe 28. When the float F reaches its upper position valve 35 will close the discharge pipe 17 with a resulting reestablishment of the pressure in supply pipe 10 and which will rapidly move the valve 25 to closed position, thereby simultaneously terminating flow of water through the pipe 28 and refill tube 29.

The level of water in the tank T may be varied upon adjustment of nuts 46 and 47 on the rods 40 which adjustment varies the position of the float F relative to the bottom of the tank T. Furthermore, the position of valve 25 in its open position can be varied for most efficient operation by adjusting the nut 27 on the threaded portion 28 of the valve stem 23.

The two part supply pipe construction provides for ready renewal of the valve seat 19 or grinding thereof since the pipe sections 11 and 12 can readily be separated upon loosening nut 13 and releasing yoke 38 from the rods 40.

While I have disclosed my invention in accordance with a single specific structural embodiment thereof, such is to be considered as illustrative only, and not restrictive, the scope of the invention being defined in the subjoined claims.

What I claim and desire to secure by U. S. Letters Patent is:

1. In combination with a flush tank, a vertically disposed water supply pipe therein, a normally closed valve in the supply pipe intermediate the ends thereof, a water discharge pipe communicating with said supply pipe below said valve, a float controlled valve normally closing said discharge pipe, and a second water discharge pipe together with a refill tube communicating with said water supply pipe above the valve therein for discharging into said tank.

2. The structure according to claim 1, wherein said first valve comprises a valve seat member within said water supply pipe having an aperture disposed axially of the pipe and a spherically surfaced seat in the lower face of the valve seat member surrounding the aperture, the upper end of said pipe being provided with an aperture axially aligned with said first aperture, an elongated valve stem extending through said aper-

tures and having a free end disposed above the upper end of the supply pipe, and a valve seat engageable member on the lower end of said stem.

3. The structure according to claim 2, wherein in said first water discharge pipe communicates with said water supply pipe at a position closely beneath said valve seat member, and said valve stem having its free end portion threaded, and a nut adjustably supported on the threaded portion and engageable with the upper end of the water supply pipe upon downward movement of said valve seat engageable member as induced by reduced water pressure occasioned by opening of the float controlled valve, the said valve seat engageable member in its lowered inoperative position being adjustably supported in positions within the water supply pipe below the point of communication of the first water discharge pipe therewith.

4. In combination with a flush tank, a water supply pipe extending upwardly therein, a water discharge pipe communicating with the water supply pipe intermediate its ends, said discharge pipe being provided with a float controlled valve, a second water discharge pipe communicating with said water supply pipe above said first water discharge pipe, and a downwardly opening valve in said water supply pipe between the points of communication of said water discharge pipes therewith, said last valve being normally held closed by the water pressure within the water supply pipe, and being gravity biased to an open

position under reduced water pressure within the water supply pipe upon opening of said first valve occasioned by downward movement of the float following a flushing operation of the tank.

5. The structure according to claim 4, wherein in said water supply pipe comprises a pair of readily separable sections, and said second valve comprising a seat member removably supported in an end of one of said sections.

6. The structure according to claim 4, wherein said float controlled valve comprises a spherically surfaced seat on the free end of said first water discharge pipe, a ball valve member engageable with said seat, a float supporting lever arm having one end thereof pivotally connected to said water supply pipe, and means interconnecting said ball valve member and said lever arm.

7. The structure according to claim 6 wherein said means comprises a plate having a spherical surfaced upwardly opening seat in which said ball valve member is freely supported, a yoke extending transversely of said lever arm and engageable therewith, and adjustable rod connections between said plate and said yoke.
